(57) **CLAIM**

The ornamental design for a pill blender, as shown and described.

DESCRIPTION

FIG. 1 is a top-right perspective view of a pill blender showing my new design;

FIG. 2 is bottom-right perspective view thereof;

FIG. 3 is a front view thereof;

FIG. 4 is a rear view thereof;

FIG. 5 is a top view thereof; and,

FIG. 6 is a bottom view thereof.

The portions shown in broken lines form no part of the claimed design.
